UNITED STATES PATENT OFFICE.

ARTHUR F. CASE, OF CLEVELAND, OHIO, ASSIGNOR TO THE WELLMAN-SEAVIER-MORGAN COMPANY, OF CLEVELAND, OHIO, A CORPORATION OF OHIO.

CAR DUMPER.

Application filed March 26, 1926. Serial No. 97,572.

This invention relates to car dumpers of the type having a car receiving cradle which is turned about an axis to dump the contents from a car supported by the cradle, 5 and the invention has particular reference to the car clamp mechanism which holds the car onto the cradle while the car is being turned to dump the car and returned to car receiving position.

10 The present invention has for its object to provide a clamp actuating mechanism which is simple in construction, easy to install and inexpensive to manufacture.

A further object is to provide clamp actuating mechanism capable of withstanding hard usage and which is so designed as to be actuated by the cradle in its dumping movements to positively apply and release the clamps.

20 A further object is to provide clamp actuating and holding mechanism which is mounted on the cradle near the pivotal axis for movement independently of the cradle and which is operatively connected to the 25 clamp on the cradle in such manner as to cause the clamp to engage the car and to hold the clamp in engagement with the car during the dumping operation and to disengage the clamp during the return movement of the cradle so that the empty car in the cradle may be replaced by a loaded car.

With the above and other objects in view the invention may be said to comprise a car dumper as illustrated in the accompanying 35 drawings hereinafter described and particularly set forth in the appended claims together with such variations and modifications thereof as will be apparent to one skilled in the art to which the invention applies.

40 Reference should be had to the accompanying drawings forming a part of this specification in which:

Figs. 1, 2 and 3 are diagrammatic end elevations of the dumper, Fig. 1 showing the cradle in car receiving position, Fig. 2 showing the cradle in a partially tilted position and Fig. 3 showing the cradle fully tilted for discharging the contents of the car thereon;

45 Fig. 4 is a side elevation of the clamp actuation mechanism; and

50 Fig. 5 is a front elevation of the actuating mechanism shown in Fig. 4.

The present invention is illustrated in 55 connection with a car dumper of the traveling type in which the dumper is mounted to travel upon suitable tracks and to receive the cars to be dumped from a railway track extending between the tracks which support 60 the dumper. The dumper consists of a supporting structure 1 which is mounted to travel upon tracks 2 which extend along opposite sides of a railway track 3, and mounted in the supporting structure 1, there 65 is a tilting cradle 4 provided with a car receiving track 5 which is directly over the railway track 3 when the cradle is in car receiving position, suitable trackways being provided for running the cars from the 70 railway track 3 up onto the car receiving cradle.

The cradle 4 is substantially U-shaped having upright sides 6 and 7 upon opposite sides of the track 5, the front side 7 being 75 somewhat higher than the side 6 and having an apron 8 over which the material is discharged as it falls from the car. The cradle 6 is suitably mounted in the supporting structure 1 to tilt about the axis of a longitudinally extending shaft 9, as will be readily seen upon inspection of Figs. 2 and 3 of the drawings. The cradle is tilted by means of hoisting cables 10 which are attached to the bottom of the cradle adjacent the front 80 of the cradle and extend underneath the cradle, up the outside of the rear side 6 over suitable guide sheaves to winding drums 11. The cradle is also provided with counterweight cables 12 each of which is attached at one end to the bottom of the cradle adjacent the rear side, extends over suitable guide sheaves 12^a at the top of the supporting structure 1 through a sheave 12^b carrying a counterweight 12^c, back over guide 85 sheaves at the top of the structure down the rear side and across the bottom of the cradle where it is attached, as shown in Fig. 3, the counterweight serving to assist the hoisting cables during the beginning of the 90 tilting movement and to lessen the momentum of the cradle after its center of gravity has been moved to a point outside the pivotal axis about which the cradle tilts.

The car dumper, in so far as above described, forms no part of the present invention, being a dumper of an old and well known type in connection with which the

present invention is illustrated, the present invention being applicable to various types of car dumpers.

The car clamp herein shown is substantially the same as that disclosed in my Patent No. 1,570,943, granted January 26, 1926, the present invention being an improvement in the mechanism for actuating the clamp. The rear side 6 of the cradle is provided on the inner side thereof with a vertical guide-way 13 in which there is slidably mounted a head 14 which carries a car engaging clamp bar 15, which is pivoted intermediate its ends at 16 to the head 14 and carries guide sheaves 17 and 18 at its opposite ends. The clamp bar 15 is adapted to extend across the top of the car, the forward end of the bar being adjacent the apron 8. A holding cable 19 is anchored to the cradle adjacent the bottom thereof and extends upwardly along the inner side of the apron 8 over the sheaves 18 and 17, down the inner side of the rear side 6 of the cradle and over guide sheaves 21 at the bottom of the cradle and on the front side thereof to a winding drum 22 which is mounted on the shaft 9. A lifting cable 23 is anchored to the cradle at the upper end of the rear side 6 thereof and extends downwardly around a sheave 25 mounted on the head 14 at the upper end thereof, extending upwardly from the sheave 25 over sheave 26 at the upper end of the side 6 and downwardly over guide sheaves 21 to the winding drum 22. The holding cable 19 and the lifting cable 23 are wound in opposite directions upon the drum 22 so that as one of these cables is wound up, the other is paid out. The car clamp tends to move by gravity into car engaging position and when the cradle is in car receiving position exerts a pull upon the lifting cable 23 tending to unwind this cable from the drum 22 and to wind up the cable 19 on the drum 22.

A lever 27 is pivoted intermediate its ends upon the shaft 9 and this lever consists of a pair of side bars 27^a which are positioned upon opposite sides of the drum 22 and which are rigidly connected at their upper ends by a cross bar 27^b and at their lower ends by a cross shaft which carries a heavy roller 28 which acts as a counterweight for the lever. The lever 27 is normally disconnected from the drum 22 and hangs in a position in which the counterweight roller 28 engages an abutment 29 on the supporting structure 1. A second lever 30 is pivoted intermediate its ends on a cross shaft 31 extending between the side members 27^a of the lever 27 below the drum 22. The lever 30 carries a roller 32 at its lower end and has a gear segment 33 at its upper end, the gear segment being formed on the arc of a circle having its center at the axis of the shaft 31. The gear segment 33 meshes with a pinion

34 which is fixed to the drum 22 so that movement of the lever 30 about the shaft 31, as an axis, causes rotation of the drum 22 in one direction or the other depending upon the direction of movement of the lever. When the cradle is in upright position, the roller 32 of the lever 30 is engaged by an outwardly extending abutment 35 carried by the side 7 of the cradle and this abutment is of such length that when the cradle is in car receiving position, the abutment 35 holds the lever 30 in a position such that the outer end portion of the segment 33 is in engagement with the pinion 34.

The drum 22 has fixed thereto a ratchet 36 which is adapted to be engaged by a pawl 37 which is pivoted intermediate its ends to the lever 27 at the end thereof above the drum 22. The pawl 37 is normally held out of engagement with the ratchet by a compression spring 39 interposed between the rear end of the pawl and the cross bar 27^b at the upper end of the ratchet. The forward end of the pawl 37 carries a roller 40 which is adapted to be engaged by a cam 41 carried by the cradle, the cam 41 being pivoted at its lower end at 42 and being yieldably held at its upper end by a compression spring 43 interposed between the upper part of the cam 41 and the cradle.

When the cradle is in car receiving position, as shown in Fig. 1, the lower end of the lever 30 is pushed to its outermost position by the abutment 35 on the cradle and the drum 22 has been rotated in a clockwise direction to wind up the cable 23 sufficiently to raise the car clamp to the position shown in Fig. 1, the holding cable 19 having been unwound at the same time sufficiently to allow the upward movement of the clamp. As soon as the cradle starts to rotate, the abutment 35 moves away from the roller 32 and the weight of the car clamp, acting on the cable 23, rotates the drum 22 in a counter-clockwise direction causing the upper end of the lever 30 to move outwardly and the roller 32 to move inwardly with the abutment 35. This movement of the drum and drum operating lever continues until the car clamp comes into engagement with the top of the car. When the cradle has moved from the position shown in Fig. 1 to that shown in Fig. 2, the cam 41 on the cradle will have swung with the cradle about the pivotal axis 9 sufficiently to engage with the roller 40 carried by the pawl 37. The action of the cam 41 is to force the pawl 37 into engagement with the ratchet 36 in opposition to the spring 39 which normally holds said pawl out of engagement with the said ratchet, the cushioning spring 43 of the cam permitting the cam to yield sufficiently to permit the pawl 37 to ride down into engagement with the next tooth in the event that it should engage with the top of a

tooth when the shaft is acted upon by the cam 41. The cam of the pawl 37 with the ratchet 36 locks the counterweight lever 27 to the drum 22 and further rotation of the cradle will cause the lower end of the lever 27 to swing inwardly away from the abutment 29 whereupon the weight of the roller 28 will act through the lever 27 upon the drum 22 tending to turn the drum in a counterclockwise direction to wind up the holding cable 19. The counterweight 28 then acts to apply tension to the holding cable 19 and to hold the car clamp down upon the top of the car and as the cradle moves to its fully tilted position, shown in Fig. 3, the weight 28 will act through the lever 27 with a gradually increasing leverage to apply the force to the car holding clamp necessary to hold the car upon its track 5 while in inverted position. As the cradle swings back to car receiving position, the counterweight 28 will first engage with the abutment 29 causing the lever 27 to remain stationary until the cam 41 has moved out of engagement with the pawl 37 whereupon the lever 27 will be freed from the drum. During the final portion of the return movement of the cradle, the abutment 35 will engage with the roller 32 and swing the lower end of the lever 30 outwardly causing the gear segment 33 to travel inwardly and rotate the pinion 34 and drum 22 in a clockwise direction, winding up the cable 23 and unwinding cable 19 to hoist the car clamp from car engaging position to the position in Fig. 1 so that the empty car is free to travel out of the cradle and a loaded car may be run into the cradle in its place.

Having described my invention, I claim:

1. A car dumper comprising a supporting structure, a car receiving cradle mounted for tilting movements on said structure, a movable car clamp carried by the cradle, and a movable actuating member mounted on a fixed support, said member being operatively connected to the clamp, said actuating member being so mounted with respect to the cradle as to be actuated by the cradle in its tilting movements to operate the clamp.

2. A car dumper comprising a supporting structure, a car receiving cradle mounted for tilting movements on said structure, a movable car clamp carried by the cradle, a counterweight lever having a stationary pivot, means for automatically establishing a connection between the counterweight lever and the clamp upon a predetermined tilting movement of the cradle to cause the counterweight lever to exert a holding action on the clamp, and means operated by the cradle in its tilting movements for moving the clamp to and from engaging position.

3. In a car dumper, a cradle adapted to receive a car, means for turning the cradle,

a movable car clamp on the cradle, a counterweight lever having a stationary pivot, means operable independently of the counterweight lever and actuated by the cradle in its turning movements for shifting the clamp, and means operated by the cradle upon a predetermined movement thereof for connecting said lever to the clamp to cause the counterweight lever to exert a holding action on the clamp.

4. In a car dumper, a cradle adapted to receive a car, means for turning the cradle, a movable car clamp on the cradle, a counterweight lever having a stationary pivot, means operable independently of the counterweight lever and actuated by the cradle in its turning movements for shifting the clamp, and means operated by the cradle upon a predetermined movement thereof for connecting said counterweight lever to said clamp shifting means to cause the counterweight to exert a holding action on the clamp.

5. In a car dumper, a cradle adapted to receive a car and mounted to turn about a horizontal axis to dump the contents from the car, a movable car clamp on the cradle, means for moving the clamp including a winding drum mounted at the pivotal axis of the cradle and a cable connecting the drum and clamp, and means operating automatically during the dumping movements of the cradle for turning the drum in a direction to apply the clamp.

6. In a car dumper, a cradle adapted to receive a car and mounted to turn about a horizontal axis to dump the contents from the car, a movable car clamp on the cradle, means for moving the clamp including a winding drum mounted at the pivotal axis of the cradle and a cable connecting the drum and clamp, and means operating automatically during the dumping movements of the cradle for turning the drum in a direction to apply the clamp, and during the return movement of the cradle for turning the drum in the opposite direction to release the clamp.

7. In a car dumper, a cradle adapted to receive a car and mounted to turn about a horizontal axis to dump the contents from the car, a movable car clamp on the cradle, means for moving the clamp including a winding drum mounted at the pivotal axis of the cradle and a cable connecting the drum and clamp, a lever pivoted adjacent the axis of the cradle, means for operatively connecting the lever to the drum, and means for operating said lever during the dumping movements of the cradle.

8. A car dumper comprising a supporting structure, a car receiving cradle mounted on said structure for tilting movements to dump the contents of a car thereon, a movable car clamp mounted on the cradle, a

clamp operating drum mounted on a stationary shaft, a cable connecting said drum and clamp, and means for actuating the drum.

5. A car dumper comprising a supporting structure, a car receiving cradle mounted on said structure for tilting movements to dump the contents of a car thereon, a movable car

10 clamp mounted on the cradle, a clamp operating drum mounted on a stationary shaft, a cable connecting said drum and clamp, and means adapted to be operated by the cradle in its tilting movements for rotating the drum.

15 10. A car dumper comprising a supporting structure, a car receiving cradle mounted in said structure for turning movements about a horizontal axis to dump the contents of a car thereon and to return to its original

20 position, a counterweight lever pivoted to turn about a fixed axis, a car clamp carried by the cradle, means for moving the clamps to and from car engaging position, and means for operatively connecting said counterweight lever to said clamp upon a predetermined tilting movement of the cradle.

25 11. A car dumper comprising a supporting structure, a car receiving cradle mounted in said structure for turning movements about a horizontal axis to dump the contents of a car thereon and to return to its original position, a counterweight lever pivoted to turn about a fixed axis, a car clamp carried by the cradle, means for moving the clamps to and from car engaging position, and means for operatively connecting said counterweight lever to said clamp upon a predetermined tilting movement of the cradle, said counterweight lever being so mounted 40 as to act upon the clamp with increasing leverage as the cradle approaches the limit of its dumping movement.

30 12. A car dumper comprising a supporting structure, a car receiving cradle mounted in said structure for turning movements about a horizontal axis to dump the contents of a car thereon and to return to its original position, a counterweight lever pivoted to turn about a fixed axis, a car clamp carried by the cradle, means for operatively connecting the counterweight lever to the clamp during the dumping movement of the cradle and for disconnecting the same during return movement, and means operated by the cradle in its dumping and return movements for shifting the clamp to and from car engaging position.

35 13. A car dumper comprising a supporting structure, a car receiving cradle mounted in said structure for turning movements about a horizontal axis to dump the contents of a car thereon and to return to its original position, a counterweight lever pivoted to turn about a fixed axis, a car clamp carried by the cradle, means for operatively

connecting the counterweight lever to the clamp during the dumping movement of the cradle and for disconnecting the same during return movement, and means operated by the cradle during its dumping and return movements and before and after the operation of the counterweight lever for shifting the clamp to car engaging position and out of car engaging position.

40 14. A car dumper comprising a supporting structure, a car receiving cradle mounted to tilt on said supporting structure to dump the contents of a car thereon, a car clamp on the cradle mounted for movement by gravity to car engaging position, clamp actuating means including a lever mounted adjacent the cradle and connected to the clamp, a member on said cradle which engages the lever when said cradle is in car receiving position to hold the clamp in releasing position and which moves out of engagement with said lever when the cradle is tilted to release the clamp and permit it to move to car holding position, and means for retaining the clamp in car holding position during the dumping operation.

45 15. A car dumper comprising a supporting structure, a car receiving cradle mounted for tilting movements on said supporting structure, a movable car clamp on said cradle, a drum mounted on a stationary shaft, cables oppositely wound on the drum and operatively connected to the clamp, means operated by the cradle in its tilting movements for operating the drum first in one direction and then in the other to move the clamp into and out of car engaging position, a counterweight normally disconnected from the drum and means controlled by the cradle in its tilting movements for connecting said counterweight to the drum and disconnecting the same therefrom.

50 16. A car dumper comprising a supporting structure, a car receiving cradle mounted to tilt on said supporting structure to dump the contents of a car thereon and to return to its original position, a car clamp on the cradle mounted for movement by gravity to car engaging position, a drum mounted on a stationary shaft, lifting and holding cables oppositely wound on the drum and connected with said clamp, a lever pivoted at the axis of the drum, a counterweight carried by said lever, means adapted to be operated by the cradle in its tilting movements for connecting said lever and drum, means for limiting the pivotal movement of said lever, and means mounted on said lever and adapted to be actuated by the cradle for operating said drum.

55 17. A car dumper comprising a supporting structure, a car receiving cradle mounted to tilt on said supporting structure to dump the contents of a car thereon and to return to its original position, a car clamp on the

cradle mounted for movement by gravity to car engaging position, a drum mounted on said cradle adjacent the axis thereof, lifting and holding cables oppositely wound on the 5 drum and connected with said clamp, a lever pivoted at the axis of the drum, a counter-weight carried by said lever, means adapted to be operated by the cradle in its tilting movements for connecting said lever and 10 drum, an abutment on the supporting structure for limiting the pivotal movement of the lever, a member movably mounted on the lever and operatively connected to the drum to actuate the same, and an abutment on the 15 cradle adapted to engage said movably mounted member to move the same and actuate the drum in a direction to lift the clamp.

18. A car dumper comprising a supporting structure, a cradle mounted for lateral tilting movement on the structure, a car clamp mounted for vertical movement on 20 one side of the cradle and movable actuating members mounted adjacent the opposite side 25 of the cradle and adapted to be actuated by the cradle in tilting, said actuating members being operatively connected to the clamp.

19. A car dumper comprising a supporting structure, a car receiving cradle mounted for tilting movements on said structure, a movable car clamp on the cradle, a winding drum mounted at the pivotal axis of the cradle, holding and releasing cables connecting the drum and clamp and wound in 30 opposite directions on the drum, drum actuating means on the supporting structure adapted to be operated by the cradle in its tilting movements to shift the clamp into and out of car engaging position, a clamp 35 holding counterweight normally disconnected from the drum, and means operated by the cradle during its tilting movements for connecting the counterweight to the drum and disconnecting the same therefrom.

40 20. A car dumper comprising a supporting structure, a car receiving cradle mounted for tilting movements on said structure, a movable car clamp on the cradle, a winding drum mounted at the pivotal axis of the cradle, holding and releasing cables connecting the drum and clamp and wound in 45 opposite directions on the drum, drum actuating means on the supporting structure adapted to be operated by the cradle in its tilting movements to shift the clamp into and out of car engaging position, a counter- 50 weight arm pivoted at the axis of the drum

and normally disconnected from the drum, and means operated by the cradle during its 55 tilting movements for connecting the counterweight arm to the cradle and disconnecting the same therefrom.

21. A car dumper comprising a supporting structure, a car receiving cradle mounted for tilting movements on said structure, a movable car clamp on the cradle, a winding drum mounted at the pivotal axis of the cradle holding and releasing cables connecting the drum and clamp and wound in opposite directions on the drum, a counter-weight arm pivoted at the axis of the drum and normally disconnected from the drum, a lever pivoted on said arm, an actuating connection between the lever and drum, an abutment on the cradle engageable with said 60 lever to actuate the same, and means carried by the cradle for connecting said counter-weight arm to the drum and for disconnecting the same therefrom.

22. A car dumper comprising a supporting structure, a car dumping cradle mounted on said structure to tilt laterally about a horizontal axis at one side of said structure to dump the contents of a car thereon and to return to car receiving position, a shaft 80 at the pivotal axis of the cradle, a drum mounted on said shaft, a car holding clamp on the cradle mounted to move by gravity to car engaging position, holding and lifting cables extending from the clamp to the 85 drum and wound in opposite directions on the drum, a counterweight arm pivotally suspended from said shaft, an abutment on the structure limiting the outward movement of the arm, a pinion fixed to the drum, 90 a lever pivoted to the counterweight arm and provided at its upper end with a gear segment meshing with said pinion, an abutment on the cradle which engages said lever during the initial part of the dumping 95 movement of the cradle and during the latter part of the return movement thereof, a ratchet on the drum, a pivot carried by the counterweight arm, means for yieldably holding the pawl out of engagement with 100 the ratchet, and a cam carried by the cradle and engageable with the pawl after a predetermined movement of the cradle for moving the pawl into engagement with the ratchet.

110 In testimony whereof, I hereunto affix my signature.

ARTHUR F. CASE.
